[57] CLAIM

The ornamental design for a food container, as shown and described.

DESCRIPTION

FIG. 1 is a perspective view of a food container showing my new design;

FIG. 2 is a right side elevation thereof, the left side elevation being a mirror image of the right side;

FIG. 3 is a front elevation thereof;

FIG. 4 is a rear elevation thereof;

FIG. 5 is a top plan view thereof;

FIG. 6 is a bottom plan view thereof; and

FIG. 7 is a perspective view thereof, in an open position.
